UNITED STATES PATENT OFFICE.

JOHN B. SALTERINI, OF NEW YORK, N. Y.

DESIGN FOR A LAMP FINIAL.

Application filed June 18, 1927. Serial No. 22,492. Term of patent 3½ years.

To all whom it may concern:

Be it known that I, JOHN B. SALTERINI, a citizen of the United States, residing at New York, in the county of New York and State of New York, have invented a new, original, and ornamental Design for a Lamp Finial, of which the following is a specification, reference being had to the accompanying drawing, forming a part thereof.

Figure 1 is a side elevation of a lamp finial.

Figure 2 is a top plan view of a lamp finial.

I claim:

The ornamental design for a lamp finial as shown.

JOHN B. SALTERINI.
